[57] **CLAIM**

The ornamental design for a bicycle display rack, as
shown and described.

DESCRIPTION

FIG. 1 is a perspective view of the bicycle display rack
showing my design, the broken lines are for illustrative
purposes only and form no part of the claimed design;
FIG. 2 is a typical side elevational view of the bicycle
display rack of FIG. 1; and,
FIG. 3 is a top elevational view of the bicycle display
rack of FIG. 1.
